UNITED STATES PATENT OFFICE

102,992

DESIGN FOR A REFRIGERATOR CABINET

John W. Norrish, Lockland, and Roland H. Money, Cincinnati, Ohio, assignors to The Crosley Radio Corporation, Cincinnati, Ohio, a corporation of Ohio

Application August 5, 1935, Serial No. 57,963

Term of patent 7 years

To all whom it may concern:

Be it known that we, John W. Norrish and Roland H. Money, citizens of the United States, residing in Lockland and Cincinnati, respectively, in the county of Hamilton and State of Ohio, have invented a new, original, and ornamental Design for a Refrigerator Cabinet, of which the following is a specification, reference being had to the accompanying drawing forming part thereof.

In the drawing:—

Fig. 1 is a perspective view of the article, showing our design.

Fig. 2 is a sectional view taken along the lines 2—2 of Fig. 1.

We claim:—

The ornamental design for a refrigerator cabinet, as shown and described.

ROLAND H. MONEY.
JOHN W. NORRISH.
